UNITED STATES PATENT OFFICE.

EDWARD M. LAMB AND EMMOR BALES, OF ADRIAN, MICHIGAN.

MACHINE FOR MAKING TOOTHPICKS.

SPECIFICATION forming part of Letters Patent No. 634,689, dated October 10, 1899.

Application filed September 1, 1898. Serial No. 689,996. (No model.)

To all whom it may concern:

Be it known that we, EDWARD M. LAMB and EMMOR BALES, citizens of the United States, residing at Adrian, county of Lenawee, State 5 of Michigan, have invented a certain new and useful Improvement in Machines for Making Toothpicks; and we declare the following to be a full, clear, and exact description of the invention, such as will enable others skilled 10 in the art to which it pertains to make and use the same, reference being had to the accompanying drawings, which form a part of this specification.

This invention relates to machines for making toothpicks, and has for its object a cutting-off device to be used in connection with the machine shown and described in Letters Patent No. 588,645, issued August 24, 1897.

In the machine shown in the patent referred 20 to a strand or splint of wood is driven forward and subjected to cutters which turn or round off the strand of wood in a nodular form—that is, that portion of the strand intended for a single toothpick is cut large or 25 swelling at its middle part and is reduced almost to a point at each end. When this strip leaves the cutting-knives, the consecutive parts that are finally to be separated into individual toothpicks are joined by a small 30 string or strip of wood that is yet to be cut through when the several picks are separated in the final operation of manufacture. In the machine shown in the patent referred to the final severing was caused by driving the strip 35 of wood between pins that projected from a fixed part of the frame and between pins that projected from a vibrating part of the machine, and at the proper moment the vibrating part of the machine was reciprocated and 40 the strip of wood severed by breaking the connecting-thread of wood. Practically it was found that the pieces did not break to uniform length, and, moreover, the ends of the pieces were more or less frayed and bent.

The object of this invention is to produce 45 a device to act in connection with the machine spoken of in place of the bars with the pins referred to, and this device cuts the picks accurately as to length with a clean cut, so that 50 the ends are unfrayed and unbroken.

In the drawings, Figure 1 is an elevation of the rear end of the toothpick-machine, show-

ing the cutting attachment thereon. Fig. 2 is a detail showing the driving mechanism of the cutter of this invention. Fig. 3 is a detail of 55 the cutting-knife.

A indicates the frame of the machine, and B a shaft journaled thereon, on which there is a mutilated miter gear-wheel b , that intermeshes with a bevel gear-wheel a , journaled in a hanger a' . On the face of the bevel-wheel a is a crank-pin a^2 , that engages in a slotted link or reach-rod b' . The link b' is pinned to one end of the lever c , the other end of which engages with a reciprocating knife-bar C , held to a fixed bar 60 D. The reciprocating knife-bar C is held to the fixed bar D by means of bolts d , that pass through the fixed bar and through slots d' in the reciprocating bar. Through the fixed bar, opposite each set of trimming-knives of the 65 machine, is a conical hole e , faced on its rear side with steel, so that the periphery of the rear edge may be kept sharp. Through the reciprocating bar C are other conical holes arranged in pairs, there being two such holes for 70 each hole through the fixed bar D, and the holes of each pair are so spaced that one of them, e' , registers with the hole e when the lever c is thrown over in one direction, and the other hole, e^2 , registers with the hole e when the lever c is thrown over in the other direction. 80

The intermitting motion of the reciprocating bar which is necessary to permit the splint of wood to feed through a definite distance before it is cut off, is produced by means of the 85 mutilated gear-wheel b , that meshes with the crank-wheel a . On the mutilated gear-wheel there are half as many teeth as there are on the crank-wheel, and a complete revolution of the mutilated wheel produces a half-revolution 90 of the crank-wheel, and inasmuch as the mutilated wheel is considerably larger in diameter than the crank-wheel there is a period through about three-fourths of a revolution of the wheel b during which the crank-wheel 95 is at rest.

By means of the slotted link b' , which engages with the crank-pin a^2 , a very quick motion is given to the reciprocating bar in both its forward and reverse motion, and the motion in both directions is timed with reference to other parts of the machine, so as to cut the splint of wood at the proper time and in proper lengths. 100

Other parts of the machine do not differ from the machine described in the patent referred to and form no part of this invention and need not be described.

5. What we claim is--

1. In a machine for making toothpicks, in combination with a fixed cutter-bar, and a reciprocating cutter-bar, a geared crank-wheel and link connection between the crank-wheel and the cutter-bar, and a mutilated gear-wheel arranged to mesh with the geared crank-wheel, whereby continuous rotary movement of the mutilated wheel produces an intermitting reciprocatory movement of the cutter-bar.

15. 2. In a machine for manufacturing toothpicks the combination of a fixed bar provided with a single perforation for each strand of material operated upon by the machine, a reciprocating cutter-bar provided with two perforations for each strand operated upon and

means for bringing the perforations in the reciprocating bar alternately into register with the perforations in the fixed bar, substantially as described.

25. 3. A cutter for severing strands of toothpicks consisting of a fixed bar having an opening therethrough with shearing-faces on each side of said opening, a reciprocating bar having a pair of openings therethrough with 30 shearing-faces between the openings, and means for actuating the reciprocating bar so as to cause the openings therein to register alternately with the opening in the fixed bar, substantially as described.

35. In testimony whereof we sign this specification in the presence of two witnesses.

EDWARD M. LAMB.
EMMOR BALES.
